Inventor:
Burtha Edith Nelson,
by her attorney,
Charles R. Searle.

UNITED STATES PATENT OFFICE.

BERTHA EDITH NELSON, OF NEW YORK, N. Y.

SKIRT GUARD.

Application filed October 17, 1923. Serial No. 669,045.

To all whom it may concern:

Be it known that I, BERTHA EDITH NELSON, a citizen of the United States, residing in the city of New York, borough of 5 Manhattan, in the county and State of New York, have invented a certain new and useful Improvement in Skirt Guards, of which the following is a specification.

The invention relates to guards or protectors 10 for ladies' skirts, adapted to receive and enfold the lower margin and edge of the garment and protect it against injury from any cause, and serving more especially to protect the margin of the skirt from moisture in wet weather.

The object of the invention is to provide a device of this character that can be readily applied to and removed from the person of the wearer, and adjustable to accommodate it to the skirt-length and waist measure, and also adjustable as to circumferential length of the garment-receiving pocket.

A further object is to provide the pocket 25 with means for clasping the skirt to hold the latter in the correct position.

Other objects and advantages of the invention will hereinafter appear, and the novel features thereof be specifically defined 30 by the appended claims.

The invention in its preferred form is clearly illustrated in the accompanying drawings, which, with the reference numerals marked thereon, form a part of this 35 specification, and in which—

Figure 1 is a perspective view showing the application of the invention upon the person of the wearer.

Figure 2 is an enlarged perspective view 40 of the device alone.

Figure 3 is a vertical section taken on the line 3—3 in Figure 2.

Figure 4 is a vertical section taken on the line 4—4 in Figure 1.

Figure 5 is a vertical section taken on the line 5—5 in Figure 2.

Figure 6 is an elevation of one of the spring clamps for closing the pocket and grasping the enfolded skirt-margin.

Figure 7 is a vertical section taken longitudinally of the pocket and partly in elevation, showing one of the casings for the arms of the spring clamp.

Figure 8 is a vertical section taken on the line 8—8 of Figure 7 and partly in eleva-

tion, showing the pocket partially closed, and a covering strip for the material of the pocket at the joint of the spring clamp.

Similar reference numerals indicate the same parts in all the figures. 60

Referring to the drawings, 10 designates a belt or band adapted to be applied about the waist of the wearer. It is adjustable as to girth in some suitable manner, as by spaced separable fasteners of the well-known "snap" type, one or more of the stud portions 12 of which are mounted on one end of the belt and a plurality of socket portions 13 on the other end portion, as shown in Figure 2. 70

Straps 14 or the like are suspended from the belt in any suitable manner; four are shown each equipped with a loop 15 through which the belt is loosely passed, thus permitting the straps to be shifted on the belt 75 to the desired positions, and the outer portion of each loop is provided on the inner face with a stud portion 16, shown in dotted lines in Figure 2, adapted to engage either of the socket portions 13 on one end of the 80 belt or other specially located socket portions 17.

The straps 14 are also adjustable as to length in any suitable manner, as by similar separable fasteners comprising stud portions 18 and socket portions 19 of which latter there may be as many, suitably spaced, as circumstances may require. 85

The lower ends of the straps 14 are sewed or otherwise secured to the upper edge of 90 the outer portion of a folded breadth of suitable material forming an open-ended pocket 20 in which the lower margin 21 of the skirt is inserted. The material may be varied but cravenette or like waterproof 95 fabric is preferred; it is doubled lengthwise upon itself to constitute a fold as at 22 forming the closed bottom of the pocket. This leaves the upper edges of the inner and outer portions of the pocket 20 free to receive therebetween the lower margin 21 of the skirt or other article of wearing apparel, as shown in Figures 3 and 4. 100

In use the adjacent ends of the pocket are designed to overlap, the one being received 105 within the other, as in Figure 1, and the lapped ends thus engaged are adapted to be secured in such adjusted position by means as separable fasteners 23 and 24 concealed within the pocket, as indicated in Figure 2, 110

a plurality of such fasteners being shown to permit the pocket to be adjusted circumferentially and held.

The inner faces of the portions forming the pocket 20 are provided with oppositely placed vertical casings 25 in which are received the arms of spaced spring clamps 26 serving when distended to hold the pocket open for facilitating the entrance of the skirt 21, and when collapsed to close the pocket and grasp closely the inclosed skirt-
margin.

The clamps consist each of two flat arms 27 and 28 of thin metal, each having holes 29 to receive stitches by which they are secured to the casings; the lower end of one arm 28 is provided with an angularly faced projecting lug 30 carrying a transverse pin 31 which serves as a pivot on which is mounted the adjacent end of the other arm 27, as in Figures 5 and 8, the arm 27 being bifurcated and formed with eyes 32 to receive the ends of the pivot or pin 31. On the arm 27 is mounted a flat spring 33 the free end of which bears against the faces 34 or 35 of the lug 30 to hold the clamp in either its closed or open position by an action analogous to that of a "knife-blade" hinge. The clamp is shown in an intermediate position in Figure 8.

To protect the material of the pocket at the fold 22 from abrasion by the clamp joint, a protecting strip 36 is introduced extending from one casing 25 to its opposite neighbor and lying between the joint and inner face of the fold as shown in Figure 8, to take the wear at that point.

The mode of application and use will be apparent. The belt 10 is applied about the waist of the wearer and properly adjusted as to girth. The skirt is then arranged with its lower edge and margin in the pocket 20, the clamps being opened to distend the pocket, the adjacent ends of the pocket

are then placed one within the other and fastened, being adjusted to the desired circumferential length, and then the clamps are collapsed to close the pocket and grasp the skirt. In general appearance the protector or guard will be that seen in Figure 1.

When not in use the guard may be folded upon itself in the closed condition and rolled up into small compass and carried in a suitable bag or other container made for the purpose.

The guard may be made in various sizes, and modifications in details of construction and arrangements of parts may be resorted to without departing from the spirit of the invention or sacrificing any of its advantages.

I claim:

1. A skirt guard comprising means circumferentially adjustable to enfold the lower margin of a garment, a waistband circumferentially adjustable, and means depending from said waistband and connected to said first-named means, for supporting the latter solely from the waist of the wearer.

2. The skirt guard described consisting of a pocket to enfold the lower margin of a garment, clamps in said pocket, means for suspending said pocket solely from the waist of the wearer, and means for adjusting said pocket circumferentially.

3. A skirt guard comprising a pocket to enfold the lower margin of a garment, suspending means for said pocket comprising straps and a belt carrying the same and adapted to be supported entirely from the waist of the wearer, pivoted skirt-clamping means in said pocket, and protecting means in said pocket between the latter and said clamping means, said pocket and suspending means being adjustable.

In testimony that I claim the invention above set forth I affix my signature hereto.

BERTHA EDITH NELSON.
